UNITED STATES PATENT OFFICE.

JAMES E. BROWN AND CHAUNCEY B. BROWN, OF BRADFORD,
PENNSYLVANIA.

CORNER-POST AND JOINT.

SPECIFICATION forming part of Letters Patent No. 687,114, dated November 19, 1901.

Application filed September 11, 1901. Serial No. 75,079. (No model.)

To all whom it may concern:

Be it known that we, JAMES E. BROWN and CHAUNCEY B. BROWN, citizens of the United States, and residents of Bradford, in the 5 county of McKean and State of Pennsylvania, have invented a new and Improved Corner-Post and Joint, of which the following is a full, clear, and exact description.

Our invention relates to a corner-post and 10 connections whereby an improved joint is formed for use in vehicle-bodies, furniture, carpentry, &c.

Reference is to be had to the accompanying drawing, forming a part of this specification, 15 which is a perspective view of a corner-post and joint embodying our invention.

The corner-post is shown at 1, and the two panels are made at a right angle, as shown at 2 and 3. These panels are mitered, as shown 20 at 12. The post is provided with dovetail tongues 4 5 of the shape shown, and the dovetail tongues are provided with longitudinal feathers 10 11, all of said parts being integral. The panels are undercut at 6, 7, 8, and 25 9 for the purpose of affording anchorage. The advantage of this arrangement is that the longitudinal feathers 10 and 11 serve to brace the dovetail tongues in place, so that even if one of the panels should split, for in- 30 stance, from any point on the faces 7 or 8 to the miter-line 12 the angles of the feathers 10 11 would coöperate with the faces 6 and 9, and thereby prevent separation of the post and panel. The anchorage of the post in the 35 panel is therefore effectively made by the addition of the feathers 10 11. It will be observed, therefore, that the post has an advantage over the ordinary post provided with dovetail tongues in that our post has extra 40 bearings, and the post therefore cannot pull away from the panels. Owing to the anchorages holding the parts so firmly together the tendency for any part to split is greatly lessened for the reason that any part that might 45 be easy to split asunder from any other part can have sufficient play to permit its severance from the main body. In fact, about the only way to separate the post from either of

the panels is to tear asunder a considerable part of either the post or the panel. The 50 parts cannot be separated by the mere chipping off of a small portion of wood, as is ordinarily the case.

Our invention admits of general use, as above stated. Not only is it particularly good 55 for all sorts of vehicle-bodies, upon the corners of which the strain is considerable, but it can be used in any relation whatever where a secure, compact, cheap, and reliable joint is needed for any purpose and where the parts 60 are intended to possess unusual strength coupled with lightness.

Having thus described our invention, we claim as new and desire to secure by Letters Patent—

1. A device of the character described, comprising a corner-post provided with dovetail tongues, said tongues having angular feathers integral therewith, said tongues and feathers extending lengthwise in the longitudinal 70 direction of the post, and a plurality of panels provided with surfaces for engaging said post and with grooves for engaging said tongues and said feathers.

2. A device of the character described, comprising a corner-post provided with dovetail tongues and angular feathers superposed upon said tongues, all of said parts being integral, and a plurality of panels provided with grooves for slidably engaging said tongues 80 and feathers.

3. A device of the character described, comprising a pair of panels provided with mitered ends and with dovetail grooves, said dovetail grooves being deepened by central channels of angular cross-section, and a corner-post provided with dovetail tongues for engaging said grooves and with angular feathers integral with said dovetail tongues for engaging said channels.

4. A device of the character described, comprising a pair of panels provided with mitered ends and with dovetail grooves and channels connected with said grooves, and a corner-post provided with V-shaped projections for 95 engaging said dovetail grooves and with mem-

bers for engaging said channels, the arrangement being such that said members in said channels and said tongues in said grooves mutually anchor each other for the purpose 5 of preventing the separation of said panels and said post.

In testimony whereof we have signed our

names to this specification in the presence of two subscribing witnesses.

JAMES E. BROWN.
CHAUNCEY B. BROWN.
